UNITED STATES PATENT OFFICE.

LOUIS KAPLAN, OF NEW YORK, N. Y.

RUBBER HEEL.

Application filed September 6, 1921. Serial No. 498,631.

To all whom it may concern:

Be it known that I, LOUIS KAPLAN, a citizen of the United States, residing at New York, in the county of New York and State 5 of New York, have invented certain new and useful Improvements in Rubber Heels, of which the following is a specification, reference being had therein to the accompanying drawing.

10 The present invention relates to cushioned heels of rubber or similar resilient material, and is particularly an improvement over the rubber heel disclosed in my copending application filed October 16, 1920, Serial No. 15 417,286.

15 The invention has for its object to provide the tread of the heel, in addition to ribs disposed one within the other in the relation as disclosed in said application, auxiliary 20 or secondary means to complement or supplement the ribs to avoid skidding or slipping, and to enhance the cushioning quality and wear resistance of the heel.

With the foregoing and other objects in 25 view, which will be apparent as the description proceeds, the invention resides in the construction and arrangement of parts hereinafter described and claimed, it being understood that changes can be made within 30 the scope of what is claimed without departing from the spirit of the invention.

The invention is illustrated in the accompanying drawings, wherein:—

Figure 1 is a plan view of the first form 35 of heel.

Figs. 2 and 3 are sections on the respective lines 2—2 and 3—3 of Fig. 1.

Fig. 4 is a plan view of a second form of heel.

40 Fig. 5 is a section on the line 5—5 of Fig. 4.

Fig. 6 is a plan view of a third form of heel.

45 Fig. 7 is a section on the line 7—7 of Fig. 6.

Figs. 8 and 9 are plan views of further modifications.

Referring to Figs. 1, 2 and 3, the heel, 50 which is molded from rubber or other equivalent material, has its tread surface provided thereon, similar to the heel shown in the aforesaid application, with the ribs 8, 9 and 10. Such ribs are of U-shape, with their ends terminating adjacent to the breast 55 or forward end of the heel, and such ribs

are broken or interrupted between their bends and terminals, where such ribs are intersected by transverse ribs 18 and 19 formed on the tread surface of the heel and arranged one within the other. The ribs 18 and 19 are continuous and extend into the broken out or interrupted portions of the main ribs 8, 9 and 10 to the sides of the heel. The ribs 8, 9 and 10 of the main set and also the ribs 18 and 19 of the secondary or auxiliary 60 set are disposed one within the other in spaced relation and are of gradually diminishing width and height from the outer to the inner ribs. The ribs 9 and 10 are spaced increasing distances from the plane of the 65 rib 8, and the rib 19 is similarly spaced from the plane of the rib 18. Thus, at the outset, the wear comes on the outer thick ribs 8 and 18 of the two sets, and when said outer ribs yield sufficiently or are worn away, the 70 ribs 9 and 10 and the rib 19 will come into contact with the underlying surface in turn, thus bringing the ribs in succession into use 75 as they are worn away from the outer ribs inward. This will continue the anti-slipping 80 and resilient qualities of the heel as it becomes worn. The U-shaped ribs with their ends extending forwardly will prevent slipping forwardly, while the ribs 18 and 19 will provide vacuum cups therein. The 85 tread portion of the heel has a cavity 7

therein between the ribs 10 and 18 and another cavity 17 within the outline of the rib 19, which cavities provide vacuum cups 90 surrounded by the ribs which will create 95 suction, especially on wet or slippery surfaces, to avoid skidding or slipping of the heel.

The ribs can be provided at suitable intervals or points with apertures 11 to assist in 95 preventing the slipping of the heel, and also, if desired, transverse notches 12.

The heel has suitable nail holes 13 extending therethrough for nailing the heel to the shoe, and such holes 13, as shown, are located 100 between the ribs 8 and 9 and the ribs 18 and 19.

In the second form of heel shown in Figs. 4 and 5, the intermediate portions or bends of the main U-shaped ribs 80, 90 and 100 105 are spaced apart, and the heel has crescent-shape vacuum cups or cavities 70 between said ribs. The secondary ribs 180 and 190 are located within the rib 100 and are reversed longitudinally with reference to the 110

- main ribs, so that the terminals of the secondary ribs project rearwardly, the ribs of the two sets diminishing in width and height from the outer rib of each set inward.
- 5 The heel also has a vacuum cup or cavity 170 between the rib 100 and the secondary ribs and extending within the rib 190. This heel also has nail holes 130 between the ribs 80 and 90.
- 10 The form of heel shown in Fig. 6 has smaller main ribs 81, 91 and 101 with their terminals extending forwardly from the rear portion of the heel, and there are two sets of secondary ribs 181 and 191 with
- 15 their bends adjacent to the forward corners of the heel and their terminals extending toward the center of the heel. The ribs of the three sets converge and meet at the center of the heel, and the heel has a
- 20 vacuum cup or cavity 71 between the sets of ribs and extending into or within the inner ribs 101 and 191. Within the intermediate portions or bends of the outer ribs 81 and 181, the heel has nail holes 131 and
- 25 vacuum cups or cavities 171 at the tread ends of said holes, and the inner ribs have their intermediate portions formed with re-entrant curves around said nail holes. The heel has other nail holes 131' located be-
- 30 tween the sets of ribs. The ribs of each set are of decreasing width and height from the outer rib inward.
- The heel shown in Fig. 8 has the ribs 83, 93, 103 and 103' located one within the
- 35 other and diminishing in width and height from the outer rib inward, and the terminals of the ribs extend angularly toward one another parallel with the breast or forward end of the heel and are of different
- 40 lengths to provide spaces between the terminals. Such spaces of the ribs are in staggered relation, and the terminals 183, 193 and 203 provide secondary anti-slipping means. The heel has a vacuum cup or cavity
- 45 73 within the inner rib 103'.
- The ribs 84, 94 and 104 of the heel shown in Fig. 9 have their terminals extended toward one another at the breast or forward end of the heel and then angularly
- 50 rearward, as at 184, 194 and 204, respectively, to provide the secondary anti-slipping means, and the heel has a vacuum cup or cavity 74 within the outline of the rib 104.
- 55 The ribs of the several forms of heels shown can be provided with apertures or transverse notches or cuts, or both, as may be desired, and the heels also have suitable nail-holes for attaching them to the shoes.
- 60 The secondary ribs or tread portions being located within the outline of the main ribs, will provide a better support for the heel, as well as providing better wearing qualities and resiliency or cushioning action. This arrangement will also reduce to

a minimum the possibility of "runovers" occurring.

The relatively large vacuum cup at the central portion of the tread surface of each heel will render the surrounding portion 70 of the heel more resilient, both vertically and laterally, than if the vacuum cup were not present, especially a relatively large vacuum cup, and the portion of the wheel surrounding the cup which is provided with 75 the ribs is thus more resilient, thereby adding to the effectiveness of the ribs. The ribs also entirely surround, substantially, the vacuum cup of each form of heel shown and described, with spaces between the ends 80 of at least some of the ribs for the restricted ingress and egress of air, it not being desirable to have the relatively large vacuum cup sealed on the surface on which the heel rests because the suction would be 85 too great. With the limited admission of air to the vacuum cup the heel is prevented from slipping, and at the same time, is prevented from sticking to the surface, especially when the surface is wet. 90

Having thus described the invention, what is claimed as new is:—

1. A heel of rubber or other resilient material having at the central portion of its tread surface a relatively deep cup of comparatively large area, and ribs protruding from said surface and substantially surrounding said cup, said ribs being located one within the other between said cup and margin of the wheel, and said ribs decreasing in height from the outer rib to the inner one toward said cup. 95

2. A resilient heel having on its tread surface a plurality of sets of protruding ribs, the ribs of each set being U-shaped and located within the other, the ribs of each set decreasing in height from the outer rib to the inner one, the intermediate portions of the ribs of said sets being at the front and rear ends of the heel with the ends of such ribs extending toward the opposite ends of the heel. 105

3. A resilient heel having at the central of its tread surface a relatively deep cup of comparatively large area, and a plurality of sets of ribs protruding from said surface and located between said cup and the margin of the heel, the ribs of each set being U-shaped and located one within the other, said ribs of each set decreasing in height from the outer rib to the inner one toward said cup, the intermediate portions of the ribs of said sets being at the front and rear ends of the heel with the ends of said ribs extending toward the opposite ends of the heel, the ribs of the plurality of sets surrounding said cup. 115

4. A resilient heel having on its tread surface protruding ribs located one within the other, the outer rib being located adja- 120

cent to the margin of the heel, and the heel having a relatively deep cavity between said outer rib and the next inner rib extending above said tread surface, and said ribs being spaced apart along said cavity.

5. A resilient heel having on its tread surface protruding U-shaped ribs with their immediate portions at the rear end of the heel and spaced apart, said ribs being lo-

cated one within the other, and the heel having cavities in its tread surface between the intermediate portions of said ribs, said cavities being comparatively deep to extend above said tread surface.

In testimony whereof I hereunto affix my signature.

LOUIS KAPLAN.
